UNITED STATES PATENT OFFICE.

HOWARD C. WOODBRIDGE, OF ROCHESTER, NEW YORK.

STEAM-VALVE LUBRICATION.

1,175,106.

Specification of Letters Patent. Patented Mar. 14, 1916.

Application filed July 3, 1915. Serial No. 38,012.

To all whom it may concern:

Be it known that I, HOWARD C. WOODBRIDGE, a citizen of the United States, and resident of Rochester, in the county of Monroe and State of New York, have invented certain new and useful Improvements in Steam-Valve Lubrication, of which the following is a specification.

This invention relates to the lubrication of the cylinder-valves of steam-engines.

In steam-engines of the ordinary slide-valve type it has been customary to lubricate both the valves and the pistons by introducing oil either into the pipe through which steam is admitted to the cylinders, or directly into the steam-chest or valve-casing. This method has not proved adequate in all cases, however, particularly in engines in which superheated steam is used.

The object of the present invention is to provide a steam-engine with means by which a constant and copious supply of oil, or other lubricant, may be fed directly to the coöperating surfaces of the steam-valve and its seat, so that the valve may be properly lubricated at all times, while the lubricant is so directly applied to the point of use that there is little waste.

To the foregoing end I provide at least one of the coöperating surfaces of the valve and its seat with a channel into which the lubricant is directly introduced. In order to convey the lubricant to and force it through said channel I employ live steam from the boiler by which the engine is supplied, this supply of steam being, however, independent of the steam-supply to the cylinder. To prevent waste of the lubricant and regulate the supply to the requirement, I also employ means, preferably embodied in the valve itself, for controlling the flow of the lubricating fluids in the said passage, in such a manner that this flow shall occur only when the surfaces of the valve and the valve-seat are in contact at the point where the channel is formed.

In the accompanying drawings:—Figure 1 is a plan-view, showing the bottom of the steam-chest, and the valve-seat, of an ordinary slide-valve of the type usually employed in connection with locomotives, these parts being provided, however, with channels and passages peculiar to the present invention; Fig. 2 is a vertical section, on a fore-and-aft plane, through the valve-seat, the valve, and the steam-chest; and Fig. 3

is a vertical section, on a transverse median plane, through the parts shown in Fig. 2, together with a diagrammatic representation of the other parts of the lubricating device.

The invention is illustrated as embodied in a slide-valve steam-engine of ordinary form, and only so much of the engine is shown as is necessary for an understanding of the invention. As shown particularly in Figs. 2 and 3, a steam-chest 5 incloses a slide-valve 6 operated by a valve-rod 7. The valve-seat comprises four parallel bars 8, 9, 10 and 11, connected at the ends by bars 12 and 13, the opening 14 between the bars 8, 10, 12 and 13 constituting the port of one end of the cylinder, the opening 15 between the bars 9, 11, 12 and 13 constituting the port of the other end of the cylinder, while the opening 16 between the bars 10, 11, 12 and 13 constitutes the exhaust-port. These parts are, or may be, all as in an ordinary slide-valve steam-engine.

In accordance with the present invention two channels 17 and 18 are formed, as shown particularly in Fig. 1, in the bars 8 and 9, these channels extending, at their ends, into the bars 12 and 13, but terminating short of the middle of these bars. The slide-valve is provided at its ends, respectively, with short channels 19 and 20, as shown in Figs. 2 and 3, these channels being formed in the bearing-surface of the valve, and in alinement with the end-portions of the channels 17 and 18 so as to register therewith in certain positions of the valve. The channels 19 and 20 are of such length as to span the distance between the ends of the channels 17 and 18 when the valve is in its middle position, but to communicate with only one or the other of these channels when the valve is moved in either direction from middle position.

A vertical passage 22, at the outer end of the valve seat, communicates with a horizontal passage 23, and this latter passage is connected, by a pipe 24, with a lubricator 25. This lubricator may be any device for feeding lubricating oil automatically, and is illustrated as of the well known displacement type. It is supplied with live steam from the boiler through a pipe 26, and this steam also flows freely through the pipe 24, so that the oil is carried through this pipe in a current of steam.

The channel 20 in the valve is connected,

by a perforation 21, as shown in Fig. 3, with the interior space of the valve, which is always in communication with the exhaust-port 16.

5 The operation of the lubricating device will now be described as a whole.

Supposing the valve to be in its middle position, live steam and oil will flow through the pipe 24 into the passage 23, and thence 10 through the passage 22 into the channel 19 in the valve-surface. From the ends of this channel the steam and oil flow into the ends of the channels 17 and 18, and thence 15 throughout the length of these channels and into the channel 20 in the valve-surface, from which they are discharged, through the opening 21, into the exhaust-port 16. Accordingly, streams of lubricating-fluid flow at this time along those parts of the 20 valve-surface which are immediately above the channels 17 and 18, the lubricant being thus applied directly to the valve-surface. If then the valve be moved from the middle position, for example to the left, as shown 25 in Fig. 2, the communication between the channel 19 and the channel 17 will be interrupted, as shown, so that when the valve uncovers the channel 17 there shall be no discharge of lubricating fluid into the steam-chest. Communication between the channel 19 and the channel 18 is continued, however, 30 so that the lubricant is applied to practically the entire working-surface of the left-hand portion of the valve. At this time the channel 20 connects the channel 18 with the exhaust-port, so that a free flow of steam and oil can occur in the channel 18, thus assuring lubrication from end to end of the valve. When the valve returns to its middle position 35 communication with the channel 17 is resumed, and upon the right-hand movement of the valve the channel 18 is disconnected, while the flow through the channel 17 is continued.

40 45 It will be apparent that the arrangement above described provides for the direct repeated application of the fluid lubricant directly to those parts of the working-surface of the valve which are most subject to the heating and scouring effect of the live steam passing to the cylinder, and it has been found in practice that this method of lubrication is so effective that it permits the use of superheated steam in connection with an ordinary slide-valve, without undue wear upon the valve, and without the use of an inordinate amount of lubricating oil.

An important advantage of the construction described resides in the fact that the 50 lubricant is forced into the steam-chest against only the comparatively slight pressure in the exhaust-port, so that the action is positive and uniform, regardless of the

variations of the pressure in the steam-chest resulting from variations in load and in the 65 position of the throttle-valve. Another advantage lies in the fact that where the engine is operated with superheated steam, the saturated steam by means of which the oil is conveyed through the channels in the 70 steam-chest is at a substantially lower temperature than the superheated steam, and consequently it tends to cool the valve-surfaces and prevent them from attaining a 75 temperature at which the lubricating effect of the oil would be impaired.

The construction hereinbefore described is designed particularly for the lubrication of the valve-surfaces, and it may be used in conjunction with other usual or suitable 80 means for lubricating the other parts of the engine-mechanism. It has been found, however, that the present arrangement will provide sufficiently for all necessary lubrication in the steam-chest and cylinder, so that further lubricating devices may be dispensed with.

While the invention has been found particularly useful in an engine where superheated steam is used, it will be apparent that 90 it may have utility in other cases, and that it is not, therefore, limited to such use nor, in general, to the details of construction and operation of the embodiment herein described and illustrated in the accompanying 95 drawings.

I claim:—

1. The combination, with a steam-valve and a valve-seat having coöperating surfaces of which at least one is provided with a channel, of means, independent of the steam-supply controlled by the valve, for introducing a current of steam and lubricant into said channel; the valve being provided with means for controlling the flow through the channel in accordance with the movements of the valve.

2. In combination with a slide-valve-seat having channels in the surfaces of its outer bars, and a slide-valve coöperating with the valve-seat, means for supplying a mixture of live steam and oil to said channels; the valve being provided with channels coöperating with those in the valve-seat to regulate the flow of the steam and oil.

3. In combination with a slide-valve-seat having channels in the surfaces of its outer bars and extending into the end-bars of the seat, a slide-valve coöperating with said seat and having channels in its ends alining and coöperating with said channels in the valve-seat; and means for introducing a lubricating fluid into the channel at one end of the valve.

HOWARD C. WOODBRIDGE.
